UNITED STATES PATENT OFFICE.

JACOB DE YOUNG, OF PROVIDENCE, RHODE ISLAND.

PUMPLESS INJECTION VALVE FOR DIESEL ENGINES.

Application filed March 17, 1925. Serial No. 16,231.

To all whom it may concern:

Be it known that I, JACOB DE YOUNG, a citizen of the United States, residing at Providence, in the county of Providence and 5 State of Rhode Island, have invented certain new and useful Improvements in Pumpless Injection Valves for Diesel Engines, of which the following is a specification, reference being had to the accompanying drawings.

This invention relates to injection nozzles for Diesel engines and has for an important object thereof the elimination of the pumping system at present employed for injection. At the present time, with each cylinder of the engine, a separate pump is usually employed having means for injecting oil into the cylinder and separately regulatable to control the amount of fuel so injected. 20 These pumps since they operate under high pressure each have a plurality of packing glands and other accompanying elements which must be adjusted and repaired and accordingly are a continual source of trouble.

An important object of this invention is the provision of a control device for injecting fuel into engines, which may be operated from a rocker arm and in which the operation is semi-automatic.

A further object of the invention is to provide in combination with a fuel feeding device a source of fuel under pressure and a source of air under pressure for forcing 35 the fuel fed to the fuel feeding device into the engine together with an automatic valve alternately cutting off the source of fuel and source of air. The fuel may be admitted without being opposed by the air pressure 40 and the air pressure may not be applied to drive the fuel back through fuel lines to its source.

A still further object of the invention is to provide a device of this character which 45 may be very easily produced and controlled.

These and other objects I attain by the construction shown in the accompanying drawings, wherein for the purpose of illustration is shown a preferred embodiment of 50 my invention and wherein:—

Figure 1 is a vertical sectional view through an injection nozzle for Diesel engines constructed in accordance with my invention; and

55 Figure 2 is a section on the line 2—2 of Figure 1.

Referring now more particularly to the drawings, the numeral 10 generally designates a firing head of a Diesel engine and 11 a cylinder having flanges 12 by means 60 of which it may be bolted to the head 10. This cylinder fits within an opening, as indicated at 13, in the usual manner and has its bore preferably directed longitudinally of the cylinder.

65 The cylinder 11 has a main bore 14 which is reduced adjacent its inner end, as at 15, to provide an injection port for the cylinder. At the point of reduction, a tapered valve seat 16 is produced. The outer end of the 70 cylinder which is in the form of a removable head 17 has an outlet opening 18 formed therein. Adjacent this outer end, the cylinder has communicating therewith a conduit 19 leading from a source of air 75 under pressure, this conduit communicating with an internal circumferential groove 20 formed in the cylinder. Inwardly from the outer end of the cylinder, a second conduit 21 having a control valve 22 therein communicates with a port 23 extending longitudinally through the wall of the cylinder and opening into the cylinder, as at 24, at a point spaced from the valve seat 16.

80 Arranged within the cylinder is a valve element including a stem 25 which projects into the reduced bore or nozzle 15. Its projection into this reduced portion is limited by a valve element 26 comprising a body having a piston fit within the bore 14 90 and a tapered lower face 27 coating with the valve seat 16. The body has longitudinally extending ports 28 opening from the upper surface thereof through the face 27 so that when the tapered face 27 is unseated, 95 the fluid will flow from above the piston to beneath the piston and between the piston and seat 16. Until the piston has moved a predetermined distance, however, open passage through the bore 15 is prevented by 100 the fact that that portion of the stem 25 which projects into the bore 15 has its portion next adjacent the piston valve 26 provided with a piston fit within this bore. After the valve has moved a predetermined 105 distance, however, from the seat, communication is established by reason of the fact that the inner end of the stem is provided with spiral grooves 29 conducting the fluids in the form of a spiral injection jet producing atomization thereof.

110 Means are provided for seating the pis-

ton valve comprising studs 30 or their equivalent projecting outwardly from the head 17 and forming a mounting for a spring seat 31 against which abuts one end 5 of a spring 32, the opposite end of which engages against a second spring seat 33 secured to the valve stem 25. When in its seated position, the outer face of the piston valve 26 is immediately inwardly of 10 the entrance 24 of the port 23 to the cylinder bore 14. Secured to the valve stem within the cylinder is a second piston valve 34 which, when the piston valve 26 is seated, occupies a position completely blocking 15 the circumferential groove 20 which affords means for admission of air to the cylinder. The cylinder is provided with a by-pass port 35 establishing communication between the ends of the cylinder at opposite 20 sides of the piston valve 34 for a purpose presently to appear. Associated with the stem is a rocker arm 36 to be actuated from the engine and to lift and open the valve against the action of the spring 25 32 at the proper intervals. The operation of this device is as follows: During the firing and exhaust periods, the piston valve 26 remains seated and during this period, the fuel oil is admitted through the conduit 21 and port 23 to the cylinder between the piston valves 26 and 34. During the admission period, the piston valves are shifted toward the outer end of the cylinder by the rocker arm 36 and during the 30 initial shifting period, the port 24 is closed by the piston valve 26, this closing occurring before communication is established with the interior of the cylinder through the port 15 by reason of the piston extension 25^a of the stem. As the shifting continues, communication is established through the port 15 and the pressure of air is brought to bear against the fluid contained within the cylinder by reason 35^a of the fact that the piston valve 34 discovers the circumferential groove 20. At the same time, this piston valve cuts off communication between opposite ends of the cylinder by covering the upper end 35^a of the by-pass port 35. When air is admitted, its pressure is supplied to force the oil through the ports 28 and grooves 29 into the cylinder. In event, any air is trapped within the cylinder during that period 40 in which oil is being injected into the cylinder, this air may escape through the by-pass port 35 and outlet 18. Regulation of the amount of oil fed is procured through the valve 22 and the air pressure introduced through the conduit 19 will, of course, be regulated to suit the needs of the particular engine to which the device is applied. If it is desired to cut off any particular cylinder of the engine, as, for example, in case of a hot bearing or overheat- 45

ed cylinder, this may be accomplished by simply closing the valve 22 without interfering with the operation of any of the other cylinders.

It will, of course, be obvious that the structure hereinbefore set forth is capable of a considerable range of change and modification without materially departing from the spirit of my invention and I accordingly do not limit myself to such specific structure except as hereinafter claimed.

I claim:—

1. In an injection nozzle for Diesel engines, a cylinder having a bore reduced at one end to form a valve seat, a fuel inlet 80 for the cylinder in the major portion of the bore and in spaced relation to such valve seat, a piston valve fitting the cylinder and having one face thereof adapted to coact with the valve seat, the piston valve having longitudinal bores opening through such face, said valve having a continuation fitting the reduced portion of the bore, the continuation at a point spaced from the piston valve a distance greater 90 than the distance between the upper face of the piston valve and the remote side of the filling port being provided with grooves extending to the end thereof, means for holding said piston valve in engagement 95 with said seat and means for shifting the piston valve out of engagement with said seat.

2. In an injection nozzle for Diesel engines, a cylinder having an oil inlet, an air 100 inlet, an outlet for fuel oil and an outlet for air trapped during admission of the oil to the cylinder, a unitary valve structure normally disposed in one position and shiftable to a second position, said valve structure when in the first named position sealing the outlet and the air inlet in the second named position sealing the outlet for trapped air and the oil inlet and in its movement from the first to the second 105 named positions sealing said oil inlet and trapped air outlet before opening the air inlet.

3. In an injection nozzle for Diesel engines and in combination, a cylinder having a bore reduced at one end to form a valve seat, a valve coacting with said seat and fitting the cylinder wall but ineffectual to prevent passage of fluids longitudinally of the cylinder when spaced from its seat, a stem for said valve having a portion engaging in the reduced portion of the bore and fitting the same and terminating in a grooved jet forming extension and an opening through the side wall of the cylinder spaced from the outer end of the valve a distance less than the length of the portion of the stem fitting such reduced bore, whereby said port is covered prior to entry of the grooved extension of the stem into the cylinder. 130

4. In an injection nozzle for Diesel engines, a cylinder having an oil inlet and adjacent the oil inlet but spaced therefrom having the bore thereof reduced to provide a valve seat, a valve stem projecting into the reduced bore and having a portion fitting the bore formed at one end with an atomizer extension and at the opposite end with a piston valve having its inner face adapted for coaction with said valve seat and its outer face fitting the walls of the cylinder, the outer edge of said piston valve being arranged immediately adjacent the inner edge of the oil inlet, the piston valve having longitudinal ports therein permitting the passage of oil therethrough when the piston valve is disengaged from said valve seat and means for forcing oil from the cylinder through the piston valve when unseated. 5. In an injection nozzle for Diesel engines, a cylinder having an oil inlet and adjacent the oil inlet but spaced therefrom having the bore thereof reduced to provide a valve seat, a valve stem projecting into the reduced bore and having a portion fitting the bore formed at one end with an atomizer extension and at the opposite end with a piston valve having its inner face adapted for coaction with said valve seat and its outer face fitting the walls of the cylinder, the outer edge of said piston valve being arranged immediately adjacent the inner edge of the oil inlet, the piston valve having longitudinal ports therein permitting the passage of oil therethrough when the piston valve is disengaged from said valve seat and means for forcing oil from the cylinder through the piston valve when unseated. 6. In an injection nozzle for Diesel engines, a cylinder having an oil inlet and adjacent the oil inlet but spaced therefrom having the bore thereof reduced to provide a valve seat, a valve stem projecting into the reduced bore and having a portion fitting the bore formed at one end with an atomizer extension and at the opposite end with a piston valve having its inner face adapted for coaction with said valve seat and its outer face fitting the walls of the cylinder, the outer edge of said piston valve being arranged immediately adjacent the inner edge of the oil inlet, the piston valve having longitudinal ports therein permitting the passage of oil therethrough when the piston valve is disengaged from said valve seat and means for forcing oil from the cylinder through the piston valve when unseated, said stem portion fitting the bore being of a length equal to the distance through which said piston valve must shift to cover said oil inlet port and close the same. 7. In an injection nozzle for Diesel engines, a cylinder having an oil inlet and adjacent the oil inlet but spaced therefrom having the bore thereof reduced to provide a valve seat, a valve stem projecting into the reduced bore and having a portion fitting the bore formed at one end with an atomizer extension and at the opposite end with a piston valve having its inner face adapted for coaction with said valve seat and its outer face fitting the walls of the cylinder, the outer edge of said piston valve being arranged immediately adjacent the inner edge of the oil inlet, the piston valve having longitudinal ports therein permitting the passage of oil therethrough when the piston valve is disengaged from said valve seat, means for forcing oil from the cylinder through the piston valve when unseated, said stem portion fitting the bore being of a length equal to the distance through which said piston valve must shift to cover said oil inlet port and close the same, said means for forcing oil from the cylinder including a source of pressure in communication with the cylinder by a port arranged adjacent the outer end of the cylinder, a piston valve rigidly connected with the first named piston valve and closing said port when the oil inlet port is open and means for shifting said piston valves to open the same. 8. In an injection nozzle for Diesel engines, a cylinder having an oil inlet and adjacent the oil inlet but spaced therefrom having the bore thereof reduced to provide a valve seat, a valve stem projecting into the reduced bore and having a portion fitting the bore formed at one end with an atomizer extension and at the opposite end with a piston valve having its inner face adapted for coaction with said valve seat and its outer face fitting the walls of the cylinder, the outer edge of said piston valve being arranged immediately adjacent the inner edge of the oil inlet, the piston valve having longitudinal ports therein permitting the passage of oil therethrough when the piston valve is disengaged from said valve seat, means for forcing oil from the cylinder through the piston valve when unseated, said stem portion fitting the bore being of a length equal to the distance through which said piston valve must shift to cover said oil inlet port and close the same, said means for forcing oil from the cylinder including a source of pressure in communication with the cylinder by a port arranged adjacent the outer end of the cylinder, a piston valve rigidly connected with the first named piston valve and closing said port when the oil inlet port is open and means for shifting said piston valves to open the same and a spring normally maintaining said valves to closed positions. 9. In an injection nozzle for Diesel engines, a cylinder having an oil inlet and adjacent the oil inlet but spaced therefrom having the bore thereof reduced to provide a valve seat, a valve stem projecting into the reduced bore and having a portion fitting the bore formed at one end with an atomizer extension and at the opposite end with a piston valve having its inner face adapted for coaction with said valve seat and its outer face fitting the walls of the cylinder, the outer edge of said piston valve being arranged immediately adjacent the inner edge of the oil inlet, the piston valve having longitudinal ports therein permitting the passage of oil therethrough when the piston valve is disengaged from said valve seat, means for forcing oil from the cylinder through the piston valve when unseated, said stem portion fitting the bore being of a length equal to the distance through which said piston valve must shift to cover said oil inlet port and close the same, said means for forcing oil from the cylinder including a source of pressure in communication with the cylinder by a port arranged adjacent the outer end of the cylinder, a piston valve rigidly connected with the first named piston valve and closing said port when the oil inlet port is open and means for shifting said piston valves to open the same and a spring normally maintaining said valves to closed positions.

oil inlet port and close the same, said means for forcing oil from the cylinder including a source of pressure in communication with the cylinder by a port arranged adjacent the outer end of the cylinder, a piston valve rigidly connected with the first named piston valve and closing said port when the oil inlet port is open and means for shifting said piston valves to open the same, the cylinder having a by-pass port bypassing the last

named piston valve when in closed position, the last named piston valve during its movement to open the fluid pressure inlet closing one end of said by-pass port to prevent communication between opposite ends of the cylinder. 15

In testimony whereof I hereunto affix my signature.

JACOB DE YOUNG.
